United States Patent

Des. 241,491
Patented Sept. 21, 1976

241,491

CHAIR CONNECTOR

Robert W. O'Halloran, 1146 Harrison St.,
Hollywood, Fla. 33020

Filed Dec. 7, 1972, Ser. No. 312,923

Term of patent 14 years

Int. Cl. D6—06

U.S. Cl. D6—191

FIG. 2

FIG. 1

Fig. 3.

FIG. 1 is a side view of a chair connector including a main body and a pin member.

FIG. 2 is an enlarged end view of FIG. 1 wherein the pin has been omitted for convenience of illustration.

FIG. 3 is an enlarged isometric view of FIG. 1 with the pin shortened for convenience of illustration.

I claim:

The ornamental design for a chair connector, substantially as shown and described.
